UNITED STATES PATENT OFFICE.

NAHUM STARKEY AND GEORGE W. CROWTHER, OF AMESBURY, MASS.

TWO-WHEELED VEHICLE.

SPECIFICATION forming part of Letters Patent No. 294,926, dated March 11, 1884.

Application filed January 14, 1884. (No model.)

To all whom it may concern:

Be it known that we, NAHUM STARKEY and GEORGE W. CROWTHER, of Amesbury, in the county of Essex and State of Massachusetts, have invented a new and useful Improvement in Shaft and Axle Connections for Two-Wheeled Vehicles, of which the following is a specification.

This invention relates to that class of passenger-carriages which are mounted upon two wheels only; and it consists in the peculiar devices and the combination thereof by which the shafts are connected with the axle, as will, in connection with the accompanying drawings, be hereinafter fully described, and specifically defined in the appended claims.

In said drawings, Figure 1 is a vertical section taken on line A A, Fig. 2, transversely to the axle and longitudinally through the rear portion of the shaft and its connecting devices. Fig. 2 is an inverted or under side plan view of the parts shown in Fig. 1. Fig. 3 is a detached side elevation, showing a modification of parts shown in Figs. 1 and 2. Fig. 4 is a top or plan view, also showing a modification of parts shown in Figs. 1 and 2. Fig. 5 is a vertical section taken on line B B, Fig. 4, and as looking toward the top of the sheet therein. Fig. 6 is an enlarged detached sectional view taken as in Fig. 1, and showing the flexible link interposed between the shaft and axle.

In said views, *a* represents the axle, which is shown as "cranked" or having a drop center, but may be either thus or straight. An arm, *b*, extends horizontally and at right angles from the axle at the opposite sides thereof, and at the proper distance from the hub-collar to receive and support the shaft *c*, which is pivotally connected with the rear arm *b* by means of an eye-plate, *d*, which is bolted, as shown, to the shaft near its rear end, and which is connected with the arm by pivot-bolt *e*, which passes through the two parts of the eye of said plate and the interposed eye of the arm, as shown. A plate, *f*, is secured to the shaft by a bolt, *h*, which passes through a longitudinal slot, *g*, in the plate, as shown in Figs. 1, 2. The front end of said plate is rounded and threaded, as shown at *i*, and

passes through the eyes of stud *j*, secured in the shaft, and is provided with a screw-nut, as shown. The rear end of said plate *f* is forked to correspond with the forks of the forward arm *b*, and the two are connected by link *k*, 55 by bolts *p*, which respectively pass through the eyes of the plate and arm and the link, as shown. In Fig. 1 said link is shown as formed with an interior folded metal plate, *l*, and an outer thickness of leather, the respective ends 60 whereof are overlapped and secured by bolt *n* in a well-known manner. In Fig. 6 the metal *l* only forms thimbles to receive bolts *p*, while the leather extends around, and is lapped and secured as in Fig. 1, and when 65 thus formed the elasticity of the leather tends to cushion the respective parts.

Instead of forming arms *b* as an integral part of the axle, they may be formed upon a plate, *v*, Figs. 4, 5, which by its ears *u* and 70 *x* can be secured upon the axle; and instead of passing a rounded portion, *i*, of plate *f* through a stud, *j*, as shown in Figs. 1, 2, an angle, *f*, may be formed at the front end of said plate, while a flat, *t*, having a corresponding perforated angle, is bolted to shaft *c* and a bolt, *u*, inserted therein, as shown in Fig. 3.

It will be obvious that by slackening the nut on bolt *h* and then turning up the nut on part *i* of plate *f* (or the nut on bolt *u* when the 80 parts are constructed as shown in Fig. 3) the plate *f* will be drawn forward, and the requisite tension may be thereby applied to link *k*. By means of the connection of shaft *c* with the rearward arm *b* by a pivotal joint between said 85 arm and plate *d* the axle is moved forward when in use without backlash or variation in the forward movement of the two, while the pivotal link-connection between the forward arm *b* and the shaft allows the latter to rise 90 and fall, as the stepping of the horse demands, without disturbing the equilibrium of the body, which may be mounted upon the axle in any desired manner, the yielding and cushioning effect of link *k* also tending to the 95 above-described result.

We claim as our invention—

1. In a two-wheeled vehicle, the combination of axle *a*, formed or provided with arms *b*, shaft *c*, plate *d*, secured to the shaft and 100

pivotaly connected with the rear arm *b*, and plate *f*, also secured to the shaft and connect-
ed with front arm *b* by a link, *k*, all substan-
tially as specified.

5. 2. In combination with axle *a*, having arms
b, shaft *c*, pivotaly connected with the rear
arm, and also connected by a link with the
front arm, and provided with means for ad-
justing the tension of said link, substantially
as specified.

10. 3. In a two-wheeled vehicle, the combina-
tion of axle *a*, having arms *b*, shaft *c*, pivotaly
connected with the rear arm, and a leather or
other flexible link uniting said shaft with
15 front arm, substantially as specified.

4. In a two-wheeled vehicle, the combina-
tion of axle *a*, having arms *b*, shaft *c*, eye-plate
d, secured to the shaft and pivotaly connected
with rear arm *b*, plate *f*, secured to the shaft
and connected by link *k* with the front axle-
arm, and formed with slot *g*, to receive bolt
h, and also formed with the rounded and
threaded part *i*, extended through stud *j*, and
provided with an adjusting-nut, all substan-
tially as specified.

20 NAHUM STARKEY.

GEORGE W. CROWTHER.
